UNITED STATES PATENT OFFICE.

FRANK LOUFEK, OF CEDAR RAPIDS, IOWA.

MACHINE FOR SETTING WHEELS.

1,296,198.

Specification of Letters Patent.

Patented Mar. 4, 1919.

Continuation in part of application Serial No. 184,923, filed August 7, 1917. This application filed August 13, 1918. Serial No. 249,659.

To all whom it may concern:

Be it known that I, FRANK LOUFEK, a citizen of the United States, residing at Cedar Rapids, in the county of Linn and 5 State of Iowa, have invented a new and useful Machine for Setting Wheels, of which the following is a specification.

This invention relates to spoke setting or wheel repairing machines especially designed for automobile wheel repair work.

The primary objects of this invention are to provide a mechanism which is adjustable for all types of vehicle wheels, which is so constructed that repair work may be done 10 speedily and with ease, which can be accurately set to give the desired dish to the wheel, and which has means to compress each spoke individually.

An important object of the invention is 15 to mount the spoke setting machine so that the machine with the wheels clamped in place may be turned in either direction at will, whereby time and labor may be saved in operating upon the wheel.

To arrive at a complete understanding of 20 the invention, reference should be made to the accompanying drawings which illustrate one embodiment of the machine. However, I do not wish to limit myself to the exact 25 construction shown, but desire to make modifications in said construction at will, provided such changes are within the scope of the appended claims.

In the drawings,—

30 Figure 1 is a perspective view showing the complete machine with a vehicle wheel clamped thereby;

Fig. 2 is a central vertical cross sectional view of the machine and wheel without the 35 pedestal;

Fig. 3 is a top plan view showing a portion of the machine; and

Fig. 4 is a detail sectional view of the spoke clamping mechanism.

The numeral 10 in the drawings designates a pedestal whose legs 11 may be of any desired number and have any shape. A shelf 12 may be and preferably is supported between the legs 11 and provides a convenient place to lay tools, varnish cans and brushes, etc. The upper end of each leg is reduced or cut away, providing a shoulder 13. These shoulders as seen in Fig. 2, support a cylindrical bearing collar 14 having

an outstanding annular base flange 15. 55 Bolts 16 or similar means fasten each leg to the bearing collar 14, so that the latter is held stationary.

A rotatable cylinder or sleeve 17 is mounted over the bearing collar 14 so as to turn 60 freely thereon. The lower edge of sleeve 17 bears against the flange 15 of the collar, while the upper edge is annularly flanged as at 18. The parts 17 and 14 constitute together what might be appropriately termed 65 the "turn-table" of the machine. A number of bolts 19 pass through flange 18 and secure the rotatable cylinder or sleeve 17 to an armed support 20. These bolts also hold a base plate 21 to said support. Supplementary bolts 19' secure the support and the base plate to each other. Thus the 70 turning of the cylinder or sleeve carries with it the main support 20 and the base plate 21.

The main support 20 preferably has four 75 radial arms 22 extending outwardly from the central circular portion, each having a rest portion 23 and a ring supporting portion 24. The said rest portion 23 and ring supporting portion 24 are arranged concentrically with the center of the support and at different elevations, the ring supporting portion being on a higher plane than the rest portion. The rest portion 23 has an inner threaded ring 25 secured to it by bolts 80 26. Under braces 27, one for each arm of the support, are fastened to said arm 28 below the ring supporting portion, and also to the rotatable cylinder or sleeve 17 at 29.

The base plate 21 has a depending center 90 boss 30 provided with a central threaded bore 31, said boss entering an opening in the center of the support 20. Midway between said boss and the periphery of the base plate rises the annular flange 32 having external threads. A table 33 has a wide circular aperture 34 centrally thereof and the depending internally threaded flange 35 which engages the flange 32 and is vertically adjustable with respect to the base 95 plate. This table engages the under side of the hubs of the wheels which are clamped in the machine and constitute what might be called a center rest for the wheels.

The inner threaded ring 25 supports a 100 threaded annulus 36 having an out-turned flange 36'. This annulus is therefore vertically adjustable. It is designed to meet the

spokes of the wheel at an intermediate point and to give them the desired inclination or "dish" with respect to the hub. The higher the annulus is adjusted above the table 33 5 the greater the dish given to the finished wheel.

Upon the outer ring supporting portion 24 of the arms 22 are placed two spaced rings 37 held apart by the spacing blocks 38. Each block 38 is held by bolts or screws 39 between the outer rings, thus forming a ring frame. Flanges 40 on the spacing blocks engage with the inner and outer edges of both rings and help secure the blocks in 10 place. There are as many of the blocks as there are arms for the support 20; and each block is fast to the rings at the point just above where the arms 22 meet the rings. The outer face of each block has a projecting 15 lug 41. With this lug a spring steel bail or loop 42 engages. The bail is pivotally mounted on a clamping lever 43, which is in turn pivoted to the extreme end of arm 22, and depends therefrom. A stop 44 prevents the clamping lever from turning too 20 inward. Obviously the bail 42 holds the block and hence the rings tight against the supporting arms when the clamp is brought into play. The spring clamps just 25 described may be replaced by any other form of clamping means, and is not considered an essential feature.

The spaced outer rings provide a runway or track for a plurality of slide brackets 45. 35 As Fig. 4 shows, these brackets have a central threaded bore 46 and are held upon the rings by outer flanges 47 and inner flanges 48. The latter have the outturned portions 49 which rest upon the upper face 40 of the upper ring and the lower face of the lower ring and form with the flanges 48 hook-like projections. Each sliding bracket receives through its threaded bore a crank or setting screw 50 with a swiveled head 51 45 on its inner end. A spur 52 formed integrally with the crank projects through a hole in the swiveled head and penetrates the wood of the rim of the wheel to hold said wheel firmly in place. It is clear that the 50 brackets 45 with the cranks 50 constitute each a spoke-compressing means. The machine is provided with a sufficient number of the spoke compressors to have one for each spoke of any wheel that may be placed 55 in the machine.

The means for holding the vehicle wheel to the machine while being worked upon, and which may be designated as a center clamp, is preferably a long clamping bolt 60 53 which extends centrally through the hub and engages at its lower end with the threads of the center boss 30 of the base plate. This bolt has two sections, the upper 54 being plain for the greater part of 65 its length with the threads 55 at the upper

end. A shoulder 56 is provided by reason of this upper section 54 being reduced or smaller in diameter than the lower section 57. The latter is threaded at 58 throughout the major part of its length, said threads holding the bolt to the base plate and allowing vertical adjustment of the bolt. 70

Surrounding the clamping bolt are two hub-engaging cones 59 and 60, of which the lower cone 59 is considerably larger than 75 the upper. The cones are really truncated and each preferably is of a 66° angle. However, other angles will serve the purpose. The central bore 61 of the lower cone 59 is smooth, and a recess 62 is formed in the 80 base of said cone to receive the shoulder 56 of the clamping bolt. On the other hand, the bore 63 of the upper cone 60 is threaded so as to engage with the threads 55. A wing nut 64, or a similar device, is turned on the 85 end of the bolt and bears against the upper cone. Obviously the distance between the cones and the pressure which they exert on the hub ends are regulated by turning the wing nut. The slant of the cones makes 90 them adjustable for a large number of different sized hubs; the bigger the hubs the farther in the cones will fit.

It will be noted that the center rest is adjustable, that the annulus is also adjustable 95 and is arranged concentrically of the outer rest; and that the ring frame is concentric with the annulus. While I have shown the center rest, annulus and ring frame mounted upon a common support, and this is the 100 preferable construction, they could be supported independently on different supports.

The operation, uses and advantages of my invention will be readily understood. When a wheel is to be repaired, it is set between 105 the outer rings with the dish uppermost and its hub receiving the clamping bolt. The table is adjusted at the desired height and the annulus is turned until it contacts with all the spokes, while the wing nut is 110 screwed down so as to clamp the hub between the upper and lower cones. The broken portion of the wheel is readily repaired as the wheel is firmly held and yet it can be turned at will because of the turntable. When the repaired wheel is to be 115 glued together again, the cranks are turned until their swiveled heads press against the rim at the desired places. Then the wheel may be left until the glue has hardened. 120

The invention is equally applicable for building new wheels. Any desired dish is given to such wheels, and they can be subjected to powerful pressure while the cement is hardening. Because the outer rings have 125 a large diameter large wheels may be built or repaired; and since the cranks have a considerable length, quite small wheels may be accommodated also in the machine. The cones automatically adjust themselves 130

to nearly all sizes of hubs. The provision of the turntable saves the workman time and trouble because he can stand in one spot and set each spoke compressor for its spoke.

5 The sliding brackets permit moving the spoke compressors in either direction along the outer rings. Hence a wheel with any number of spokes is quickly accommodated. By using this machine one saves time and 10 labor and can do better work than with most spoke setting machines.

This application is a continuation in part of the application filed by me August 7, 1917, Serial Number 184,923.

15 What is claimed is:—

1. In a wheel-compressing machine, the combination with an adjustable center rest, of an adjustable annulus concentrically of the center rest, a ring frame about the adjustable annulus and concentric therewith, and a plurality of setting members carried by the ring frame.

2. In a machine of the character described, a support, an adjustable center rest on said support, an adjustable annulus concentrically of the center rest, a ring frame about the adjustable annulus and resting upon the support, and a plurality of setting members carried by the ring frame for engaging the rim of the wheel when placed upon the rest and annulus.

3. In a machine of the character described, a support, an adjustable center rest on said support, an adjustable annulus concentrically of the center rest, a ring frame about the adjustable annulus and resting upon the support, a plurality of setting members carried by the ring frame for engaging the rim of the wheel when placed upon the rest and annulus, and means for detachably clamping the ring frame to the support.

4. In a machine of the character described, a support, an adjustable center rest on said support, an adjustable annulus concentrically of the center rest, a ring frame about the adjustable annulus and resting upon the support, a plurality of setting members carried by the ring frame for engaging the rim of the wheel when placed upon the rest and annulus, means for detachably clamping the ring frame to the support, a center clamp on the support, slide brackets for the setting members adjustably engaged with and slidably on the ring frame, and a holding ring carried by the support for the adjustable annulus.

5. In a machine of the character described, a support, an adjustable center rest on said support, an adjustable annulus concentrically of the center rest, a ring frame about the adjustable annulus and resting upon the support, a plurality of setting members carried by the ring frame for engaging the rim of the wheel when placed upon the rest and annulus, means for detachably clamping the

ring frame to the support, a center clamp on the support, slide brackets adjustably engaged with the ring frame for the setting members, a holding ring carried by the support for the adjustable annulus, and a base 70 plate on the support for the adjustable center rest.

6. In a wheel-compressing machine, a support carrying a center rest, a ring frame connected to the support, and individual 75 spoke-compressing means slidable laterally in either direction on the ring frame and removable therefrom, said means comprising a slide bracket, and a setting screw passing through the bracket and adapted to engage the rim of a wheel in line with the spoke.

7. In a wheel-compressing machine, a support carrying a center rest and a ring frame, said ring frame being composed of upper 85 and lower rings spaced apart, and individual spoke-compressing means slidable laterally in either direction on the ring frame, and each comprising a block mounted between and guided by the said rings, and a setting screw passing through the block and adapted to engage the rim of a wheel in line with the spoke.

8. In a wheel-compressing machine, a support carrying a center rest and a ring frame, 95 said ring frame being composed of upper and lower rings spaced apart, slide brackets mounted on the ring frame and each comprising a central block and hooked flanges embracing the rings, and setting members 100 mounted in the brackets and movable therewith along the ring frame in either direction.

9. In a wheel-compressing machine, a support, a center rest adjustable vertically with 105 respect to the support, an annulus adjustable vertically relative to the support and arranged concentric with the center rest, and a ring frame concentric with the center rest and carrying spoke-compressing means, said 110 ring frame being mounted upon the support and said spoke-compressing means being mounted upon the ring frame to move laterally thereon in either direction.

10. In a wheel-compressing machine, an 115 armed support, a center rest attached to said support, a ring frame resting on the outer ends of the arms of said support, means for clamping the ring frame to the arms of the support and holding the ring frame against 120 movement on the support, said clamping means being extended below the arms of the support, and a plurality of spoke-compressing means carried by the ring frame.

11. In a wheel-compressing machine, an 125 armed support, a center rest attached to said support, a ring frame resting on the outer ends of the arms of said support, said ring frame being composed of upper and lower rings spaced apart, spacing blocks rigidly 130

secured between the rings coincident with the location of the arms of said support, clamping devices engaged with the arms of the support and the ring frame for holding the latter upon the support, and individual spoke-compressing means slidable laterally in either direction on the ring frame between the rigidly mounted blocks and each comprising a block guided by the said rings and a setting screw.

12. In a wheel-compressing machine, an armed support, a center rest attached to said support, a ring frame resting on the outer ends of the arms of said support, individual spoke-compressing means slidable on the ring frame, and means for clamping the ring frame to the arms of the support, said means comprising a projecting lug extending from the ring frame, a clamping lever, and a spring bail between said lever and said lug, said lever being mounted upon said support.

13. In a wheel-compressing machine, a support, a base plate fixed to the support, an adjustable table constituting a center rest, threaded flanges carried by the table and the base plate respectively and providing for the adjustment of said table, and spoke-compressing means mounted on the support.

14. In a wheel-compressing mechanism, an armed support, a center rest on said support, a ring frame supported on the arms of the support, clamping means secured to the outer ends of the arms of the support for holding the ring frame against relative movement on the support, and compressing means for the spokes adjustably carried by the ring frame and independent of the said clamping means.

15. In a wheel-compressing machine, an armed support, an adjustable center rest mounted on the support, an interiorly threaded stationary ring concentric with the center rest and fastened to the arms of the support, an annulus with a depending externally threaded flange engaging the stationary ring, said annulus being adjustable vertically to give the desired dish to the spokes of a wheel, and a ring frame with spoke-compressing means carried by the said support.

16. In a machine of the class described, a support, a base plate fixed to the support and having a depending internally threaded boss, a hub clamping means adjustably held in said boss, an externally threaded flange rising from the base plate concentrically of the boss, an adjustable table having an internally threaded flange engaged with the flange of the base plate, and setting members concentric with the boss.

17. In a machine of the class described, a support having a threaded boss, a hub clamping bolt threaded in said boss, said clamping bolt rising from the boss and hav-

ing its upper end adapted to enter the hub of a wheel, means mounted on said bolt for holding the same to the hub, a table forming a center rest, an adjustable connection between the support and the table, and setting members concentric with the boss.

18. In a machine of the class described, an adjustable center rest, setting members, and a hub clamping bolt engaging with the center rest and vertically adjustable with respect thereto.

19. In a machine of the class described, an adjustable center rest, setting members, and a single clamping bolt adjustably engaged with the center rest at its lower end, and carrying self-adjusting hub engaging cones at its upper end.

20. In a machine of the class described, an adjustable center rest, setting members, and a clamping bolt adjustably engaged at its lower end with the center rest, said bolt carrying a lower slideable hub engaging cone and an upper screwable hub-engaging cone at its upper end.

21. In a machine of the class described, an adjustable center rest, setting members, and a single clamping bolt adjustably engaged with the center rest at its lower end, and carrying self-adjusting hub engaging cones at its upper end, each of said cones being truncated and concentric with said bolt.

22. In a machine of the class described, an adjustable center rest, setting members, and a single clamping bolt adjustably engaged with the center rest at its lower end, and carrying self-adjusting hub engaging cones at its upper end, said cones being mounted on the bolt longitudinally and inverted with respect to each other, the lower one of the cones being the larger.

23. In a machine of the class described, a pedestal or stand, an armed support rotatable on said stand, an adjustable center rest on said support, an adjustable annulus about the center rest, a ring frame surrounding the annulus and resting on the support, and setting members carried upon said ring frame, said elements being movable as a unit with the support on said pedestal.

24. In a machine of the class described, the combination with the pedestal having a bearing collar at its upper end, a rotatable sleeve fitted around said collar, a support rigidly secured to said sleeve, and wheel supporting means and setting members mounted upon said support and movable as a unit therewith.

25. In a machine of the class described, the combination with the pedestal having a bearing collar at its upper end provided with an outstanding base flange, a rotatable sleeve fitted around said collar and bearing upon said flange, a support rigidly secured to said sleeve, and wheel supporting means

and setting members mounted upon said support and movable as a unit therewith.

26. In a machine of the character described, the combination with the pedestal, of an armed support, means mounted upon said support for supporting a wheel in proper position, setting members also mounted upon said support, and co-acting elements carried by the pedestal and sup-

port and forming a turn table to permit the 10 turning of the support on said pedestal.

In testimony that I claim the foregoing as my own, I have hereto affixed my signature in the presence of two witnesses.

FRANK LOUFEK.
